UNITED STATES PATENT OFFICE.

LOUIS A. BEAN, OF DENVER, COLORADO.

AUTOMOBILE HEADLIGHT.

Application filed May 19, 1924. Serial No. 714,353.

To all whom it may concern:

Be it known that I, LOUIS A. BEAN, a citizen of the United States of America, residing at Denver, in the county of Denver and State of Colorado, have invented certain new and useful Improvements in Automobile Headlights, of which the following is a specification.

This invention relates to automobile headlights more particularly of the type as disclosed in the applicant's prior application Patent No. 1,480,364, filed April 16, 1923, patented January 8, 1924, and has for its principal object the provision of a reflector for an automobile headlight which will give a fan shaped beam of light, such as projected by the reflector of said prior application, but which will give a more intense light directly ahead than would the previous reflector.

Another object is to provide a reflector whose projected beam will be relatively narrow in vertical projection so as to prevent glare to an approaching driver.

A further object of the invention is to efficiently incorporate with an automobile headlight a light of lesser intensity which may be used as a parking light and may, if desired, be provided with a color screen so as to produce a novel and ornamental effect.

A still further object of the invention is to provide a pair of automobile headlights which together will project a wide band of brilliancy ahead of an automobile extending through a wide horizontal and narrow vertical band.

Other objects and advantages reside in the detail construction of the invention, which result in simplicity, economy, and efficiency, and which will become more apparent from the following description.

In the following detailed description of the invention reference is had to the accompanying drawing which forms a part hereof. Like numerals refer to like parts in all views of the drawing and throughout the description.

In the drawing:

Fig. 1 is a face view of my improved headlight.

Fig. 2 is a cross-section taken on the horizontal center line of the same, line 2-2, Fig. 1.

Fig. 3 is a similar cross-section taken on the vertical center line, line 3-3, Fig. 1.

Fig. 4 is a diagrammatic plan illustrating the projection of a pair of my improved headlights on an automobile.

In Figs. 2 and 3, typical light beams have been illustrated, the incident rays being shown in solid line and the reflected rays being shown in broken line.

I attain the principal objects of my invention by means of a novel reflector, 10, in which is placed a light source 11. The reflector 10 comprises two horizontally opposed reflecting surfaces 12 and 13, one to each side of the light source 11. The surface 12 is substantially a semi-paraboloid, while the surface 13 is concave and comprises what is practically one-half of the reflector as disclosed in the applicant's said prior application. A horizontal section through the surface 13 discloses practically an elliptical curve with the light source placed on the shorter axis of the ellipse. A horizontal section through the surface 12 discloses a parabolic curve with the light source placed on its axis.

The curved edges of the open sides of the portions 12 and 13 are tangentially connected by straight edges 14 and 15. Extending from the straight edges 14 and 15, to a point back of the light source 11, are two vertically opposed triangular shaped reflecting surfaces or parabolic planes 16 and 17 which, when cut by a plane parallel to the face of the reflector, disclose straight lines, and when cut by a perpendicular plane, at right angles to the face of the reflector, disclose substantially a parabolic curve. The triangular shaped surfaces 16 and 17 are tangent throughout to both the parabolic surface 12 and the concave surface 13.

The reflector therefore comprises four distinct reflecting surfaces, to-wit, 12, 13, 16 and 17 having a common apex at the axis of the reflector. The triangular surfaces 16 and 17 present substantially right triangles, one leg of each coinciding in position and length with one of the two parallel lines 14 and 15, and the other leg of each lying on the vertical axis of the reflector. The latter legs are the lines of joining to the semi-parabolic surface 12 while the hypotenuse of each are the lines of joining with the concave surface 13.

It will be noted that this construction places the light source to one side of the vertical center line of the reflector and upon the horizontal center line.

105

110

The effect of the reflector contour on the rays of light will now be described. The rays of light projected toward the surface 12 of the reflector, designated by the numeral 18, will be reflected substantially at right angles to the reflector opening, as indicated at 19.

These rays illuminate the area directly ahead of the automobile as indicated at 19', Fig. 4. The rays which are projected toward the surface 13 of the reflector will be reflected in a wide fan shaped beam. These rays will illuminate the area to one side of the automobile, as indicated at 20, Fig. 4.

The action of the surface 13 upon the light rays has been well described in the said prior application and will be described briefly herein. The rays which strike the portion 13 of the reflector nearest the light source will be directed at an angle to one side thereof, as indicated at 21; as the distance from the light source is increased, the angle of these rays with the axis of the light source will also increase, reaching their maximum angle at the portion of the reflector designated at 22 and indicated by the rays 23. From this point on to the extremity of the reflector the angle of the reflected rays with the axis of the light source decreases, as indicated at 24. The action of the light rays on the triangular surfaces 16 and 17 directly above and below the light source 11 is indicated in Fig. 3, the reflected rays 25 being directed straight forward.

The angle of the beams at any line in the surface 13 radial to the light source 11 will vary from that of Fig. 3 to that of Fig. 2 depending upon its angle from the vertical center line.

It is desired to be understood that, the rays indicated are more or less theoretical and assume that the light source is a point of light. Practically, however, such a point of light is impossible to obtain and the angle of the light rays will vary and the rays themselves will diffuse and intermingle over the entire lighted area.

It is intended that two of the reflectors 10 be carried by an automobile, as indicated in Fig. 4. When thus carried the rays from the portion 13 of the reflector will be directed to each side of the automobile as indicated at 20; the rays from the portion 12 of the reflector will be directed substantially straight ahead of the automobile, as indicated at 19', the result being, that a very wide area ahead of the automobile is brilliantly illuminated, while the rays, which in the usual parabolic conoid type of the reflector are directed upward or downward at various angles, are spread in a wide fan shaped beam giving useful illumination.

In Fig. 4, the right and left headlights are designated by the numerals 25 and 26

respectively. The right headlight 25 spreads its side rays to the left of the automobile while the left headlight 26 directs its rays to the right thereof. The reflectors may, of course, be interchanged from the position shown in Fig. 4, so that the left headlight will direct its rays to the left and straight ahead while the right headlight directs its rays to the right and straight ahead.

The reflector 10, is preferably, placed within a housing 27, in the face of which a lens 29 is carried, the light source 11 being on the center line of the housing. The contour of the open side of the housing 27 is similar to the contour of the open side of the reflector 12, but, since the light source is concentric to the housing 27 and eccentric to the reflector 10, a crescent shaped section of lens 28 will be left between the reflector opening and the end of the housing opening which will not be illuminated by the light source 11. This section of lens may be frosted or colored, as indicated in Fig. 1, to act as a parking light and is illuminated from a second light source 29, placed relatively close to the light source 11 so as to be partially covered by the projecting edge of the reflector 10. The rear side of the reflector 10, indicated at 30, is brightened or silvered to act as a reflecting surface and the interior face of the housing 27, at 31, is similarly prepared to act as a reflecting surface. This results in diffusing the rays from the light source 29 and directing them against the portion 28 of the lens 29, as indicated in Fig. 2, thus obtaining an even distribution of light over the colored or frosted area.

The light sources 11 and 29 are carried in slidably mounted sockets 32 and 33 respectively, which may be focused and set in any desired position in the housing 27 by means of set screws 34. The lens 29 and the reflector 10 are held in place by a channel rim 35 which is formed in two sections clamped together by means of clamp screws 36.

It is desired to be understood that it is not essential to the invention that the portions 12 and 13 of the reflector join on a vertical line passing through the light source, since it has been found that there is no noticeable difference in efficiency produced by placing the light source 11 at a short distance to the right or left of the joining line. It is also desired to be understood that the curves designated as elliptical and parabolic are not necessarily limited to perfect parabolas and ellipses, but may be made any substantial variation thereof.

While a specific form of the improvement has been described and illustrated herein, it is desired and understood that the same may be varied, within the scope of the

appended claims, without departing from the spirit of the invention.

Having thus described the invention, what I claim and desire secured by Letters

5 Patent is:

1. In a light projecting apparatus, the combination in a reflector having a horizontally placed oblong opening, the vertex of said reflector being to one side of the vertical and on the horizontal center line thereof, upper, lower, and side portions all radiating from the vertex of said reflector, one of the side portions presenting substantially a parabola in horizontal cross section 10 the other side portion presenting substantially a portion of an ellipse in horizontal cross section, the upper and lower portions each comprising substantially triangular surfaces presenting an arc of a parabola in 15 an axial section and a straight line in a horizontal section said upper, lower, and parabolic sections arranged to reflect rays axially, said elliptical section arranged to reflect rays horizontally to one side of said 20 25 axially reflected rays.

2. The combination in a reflector, having an oblong opening defined by two parallel straight lines tangentially connected by semi-circular ends, of two triangular-shaped surfaces of a base equal to the length of, and coinciding with, said two parallel straight lines and extending back on a substantially parabolic curve to the apex of said reflector; a third surface representing 30 35 substantially a semi-paraboloid tangentially joined to said two triangular surfaces on the

vertical axis of said reflector and having a base coinciding with one of said semi-circular ends and a fourth concave surface tangentially joining the opposite edges of said 40 triangular surfaces and having a base coinciding with the other of said semi-circular ends.

3. In a light projecting apparatus, the combination of a reflector having an oblong 45 opening defined by two parallel straight lines connected by semi-circular ends, said reflector comprising, a pair of similar triangular-shaped surfaces having a common apex at the axis of said reflector, said triangular surfaces presenting right triangles one leg of each coinciding in position and length with one of said two parallel lines and the other leg of each lying on the vertical axis of said reflector; a parabolic surface, comprising a semi-paraboloid tangentially joined to said two triangular surfaces on said vertical axis and having a base coinciding with one of said semi-circular 50 ends and a concave surface tangentially joining said triangular sides along the hypotenuse of each triangular surface; and a light source arranged in focus with said reflector whereby said triangular-shaped and said parabolic surfaces will project substantially parallel rays of light forwardly and said concave surface will project diffusing rays of light to one side of said parallel rays of light.

In testimony whereof, I affix my signature.

LOUIS A. BEAN.
